UNITED STATES PATENT OFFICE.

SETH S. AVERY, OF PLEASANT LAKE, INDIANA.

AIR-PUMP.

1,347,434.

Specification of Letters Patent. Patented July 20, 1920.

Application filed February 18, 1919. Serial No. 277,807.

To all whom it may concern:

Be it known that I, SETH S. AVERY, a citizen of the United States, and a resident of Pleasant Lake, in the county of Steuben 5 and State of Indiana, have invented a new and Improved Air-Pump, of which the following is a full, clear, and exact description.

The present invention relates to pumps, 10 and while the same pertains more particularly to hand pumps for inflating pneumatic tires and the like, the several features thereof are equally adaptable to pumps driven by power.

One of the principal objects of the invention is to provide a single cylinder pump in which the operation is double acting.

A further object of the invention is to construct a pump in such manner that the 20 up-stroke of the piston is limited in its length.

A still further object of the invention is to construct the pump cylinder in such a manner that the up-stroke of its piston is 25 cushioned by a body of air which is trapped in the top of the pump cylinder.

A still further object of the invention is to so construct a pump that any of the several parts may be renewed from time to 30 time as occasion may require.

Reference is made to the accompanying drawings forming a part of this specification, in which the figure is a vertical sectional view of a pump constructed in accordance with the present invention.

The device comprises a base 40 which has an interiorly screw-threaded flange 41, with which the pump cylinder 42 is adapted to engage. The lower end of the cylinder 42 40 being provided with a screw thread 43 for this purpose. The cylinder 42 is provided near its upper end, with a port or the like, 44, and secured to said upper end is a casting 45, which is provided with an air passage 46, which in turn is controlled by a valve 47. The upper end of the cylinder

42 is provided with an annular flange 48. The casting 45 is adapted to be moved into engagement with the flange 48, and retained 50 in contact therewith by means of an annular collar or the like, 49. Clamped between the annular collar 49 and the flange 48, is a washer 50 and a suitable packing 51, said packing having a downwardly projecting annular flange 52, the lower portion of which lies within the confines of

the upper end of the cylinder 42. It is to be noted that the port 44 in the side of the cylinder 42, is at a point remote from the end of said cylinder, the purpose of 60 which location will be hereinafter set forth.

Mounted for movement longitudinally of the cylinder 42, is a hollow piston 55, and screw-thread into the inner end of said hollow piston 55 is a piston head 56, provided 65 with an air passage 57, which is controlled by a ball valve 58 adapted to engage against the seat 59. Secured to the outer face of the piston head 56, is a packing 60, said packing being secured in place by means of 70 a plate 61 and a bolt 62. This bolt is provided with a longitudinal air passage 63, which communicates with the valve chamber 64 in which the valve 58 is mounted.

Threaded into the outer end of the piston 55, as at 65, is a casting 66, which is provided with an inlet port 67. Projecting from this casting 66, is a stem 68, upon the upper end of which is mounted a handle 69. Depending from the casting 66, is an 80 annular flange 70, and suitably secured to the bottom edge of said annular flange 70, is an air screen 71.

Upon the up-stroke of the piston 55, fluid is drawn into the cylinder 42, the fluid 85 passing in through the inlet passage 67, through the screen 71, hollow piston 55, passage 57, valve chamber 64, and passage 63 through the bolt 62. Upon the down-stroke of the piston 55, it will be seen that 90 the fluid will pass around the packing 60, to the space 72 between the piston 55 and the cylinder 42, from which space 72, the fluid passes through the medium of the passage 46 and nipple 73 to the exterior of 95 the cylinder 42. Upon the up-stroke of the piston 55, the fluid remaining in the space 72 is forced out through the passage 46 and the nipple 73, and, at the same time, a new charge of fluid is taken into the cylinder 42 in the manner hereinafter described.

As above stated, the port 44 which leads from the cylinder 42, is somewhat removed from the end of said cylinder and by this construction it will be seen that as the packing 60 passes said port, it will be closed. Upon closing the port 44, a certain amount of fluid will be trapped in the space 74 between the port and the end of the cylinder. 110 The fluid thus trapped in the upper end of the cylinder 42, forms a cushion for the

end of the up-stroke of the piston 55, thus providing means by which the shocks and jars to which this type of pump is often subjected, are eliminated.

5 Having thus described the invention, what is claimed is:

A pump comprising a base, an internal screw-threaded flange projecting from the top face of said base, a pump cylinder having threaded engagement with said flange and having its opposite end open, a hollow pump piston movable in the cylinder, a valve mounted in the piston head, an in-

take opening in the other end of the piston, a collar carried by the open end of the 15 pump cylinder and provided with an outlet passage, said collar having screw-threaded engagement with the first-mentioned collar, and a washer interposed between said collar and the end of the cylinder, said washer forming an air-tight joint between the cylinder and the hollow piston in its movement within the cylinder, substantially as described.

20 SETH S. AVERY.
